CLOSURE

Application filed January 9, 1929. Serial No. 331,174.

This invention relates to improvements in bayonet-joint closures of the type provided with opposed locking fingers for co-operation with opposed cam portions of the device having the opening to be closed.

The general object of the present invention is the provision of a closure of the type described having an improved locking member provided with simple yet especially effective means for enabling the locking fingers of said locking member to engage the cam portions of the device to be closed with the desired amount of resiliency.

Further objects of the invention are in part obvious and in part will appear more in detail hereinafter.

In the drawing, which represents one suitable embodiment of the invention, Fig. 1 is a central vertical sectional view of the present improved closure detachably connected to a tubular neck, the view through the closure being on the line 1—1, Fig. 2; Fig. 2 is a bottom view of the closure on the line 2—2, Fig. 4; Fig. 3 is a top plan view of said closure; Fig. 4 is a central vertical sectional view of said closure on the line 4—4, Fig. 2; Fig. 5 is a top plan view of the neck shown in Fig. 1; and Fig. 6 is a central vertical sectional view of said neck on the line 6—6, Fig. 5.

The closure illustrated in the drawing includes a one-piece body member which constitutes the closure inner wall, said body member comprising a central cup-shaped portion and a horizontal flange portion 1 of annular form extending outwardly from the top of the cup-shaped portion. Said cup-shaped portion includes a cylindrical side wall 2 and a circular bottom wall 3 and within the chamber 4 of this cup-shaped portion is arranged the generally rectangular sheet metal body portion 5 of the closure locking member. At each end of said body portion 5 is a locking extension or finger 6 of reduced width and arched upwardly in cross section, said fingers projecting outwardly through opposed openings 7 in the side wall 2 of the cup-shaped portion of the closure inner wall, as clearly indicated in Fig. 1. The width of these fingers is sub-

stantially the same as that of the openings 7 so that said fingers are prevented from turning relative to the closure inner wall. Said fingers are normally held at the top of the openings 7 by two resilient arms 8 each having one of its ends connected to the body portion 5 of the locking member and its other end extending downwardly into yielding engagement with the bottom wall 3 of the cup-shaped portion of the closure inner wall. These arms extend in opposite directions in substantially parallel relation and are shown as integral parts of the locking member body portion 5.

The closure inner wall is covered by a suitable cover member which constitutes the outer wall of the closure and which comprises a circular dome-shaped top portion 10 and a depending cylindrical skirt portion 11. The horizontal flange portion 1 of the closure inner wall is secured to this cover member or outer wall at the junction of the top and skirt portions thereof, preferably by a crimping operation. In order to positively interlock these parts and thereby prevent relative rotary movement thereof, the horizontal flange portion 1 of the closure inner wall is provided with an outwardly extending projection 12 which is adapted to lie within and fit a correspondingly shaped recess formed by pressing outwardly a portion 13 of the cylindrical skirt portion 11 of the closure outer wall. Preferably, and as shown, said pressed out portion 13 is a continuation of an upwardly pressed out ridge 14 which extends diametrically across the top portion 10 of the closure outer wall.

In the present embodiment of the invention, an inverted cup-shaped member 18 is positioned within and at substantially the top of the cup-shaped portion of the closure inner wall, as clearly indicated in Figs. 1 and 4. Said member 18 separates the chamber 4 within the cup-shaped portion of the closure inner wall from the chamber 19 formed by the dome-shaped portion 10 of the closure outer wall. One or more openings 20 are provided in member 18 for establishing communication between these two air chambers, communication between cham-

ber 4 and the device having the opening to be closed being established by the openings 7 of the closure inner wall and communication between the upper air chamber 19 and the outside atmosphere being established by 5 one or more openings 22 in the margin of the horizontal flange portion 1 of the closure inner wall.

In the present embodiment of the invention, here illustrated, the tank 25 or other device to be closed has its opening 26 surrounded by an upwardly extending neck having a tubular body portion 27. Said body portion may be an integral part of the 10 tank or separate therefrom and suitably secured thereto, the latter arrangement being 15 here shown with said body portion provided with a laterally extending base flange 28 adapted to be welded or otherwise suitably 20 secured to said tank.

At its upper end, said neck body portion is provided with an inwardly extending transverse wall 30 which terminates in a 25 depending flange 31. At two diametrically opposite points, parts of the wall 30 and the flange 31 are cut away to provide two passageways 32 through which are adapted to be passed the fingers 6 of the closure locking member, as will later appear. The cutting away of parts of said wall 30 and flange 30 31 provides two depending flange portions 31 of substantially semi-circular form and the bottom edges of these flange portions are inclined to provide cam surfaces 33 with 35 which cooperate the closure locking fingers 6 in effecting detachable connection of the closure to the neck. In order to limit rotary movement of the closure locking fingers up 40 along the cam surfaces 33, each flange portion 31 is provided at the rear of its cam surface with a depending stop projection 34 and just in advance of these projections, each cam surface is provided with a recessed 45 portion or dwell 35, in which dwells the closure locking fingers seat when the closure is in fully locked position on the neck.

The closure is applied to the neck in the usual manner of bayonet-joint connections, the closure locking fingers 6 being passed 50 down through the passageways 32 of the neck. The closure is then turned in a clockwise direction which causes the closure fingers to ride up the cam surfaces 33 until they reach the dwells 35 therein, further 55 rotary movement of said fingers in this direction being prevented by the stop projections 34. As said fingers ride up the cam surfaces 33, they move downwardly in openings 7 of the closure inner wall, such downward 60 movement being permitted by the resiliency of the arms 8 of the closure locking member, said arms tending to move to flattened or collapsed position, as indicated in Fig. 1.

To remove the closure, it is only necessary 65 to turn it in the reverse direction, whereupon

the closure locking fingers leave the dwells 35 and ride down the cam surfaces 33 to the passageways 32, after which the closure can be readily lifted from the neck.

Preferably, the closure is provided with a 70 yielding gasket 38 which is adapted to snugly surround the cup-shaped portion of the closure inner wall and to engage the lower surface of the horizontal flange portion 1 thereof. While engagement of the gasket 75 38 with the cup-shaped portion of the closure inner wall is usually snug enough to maintain the gasket in position, said gasket can not escape from the closure due to the outwardly extending locking fingers 6 of the closure locking member. When the closure is applied to the neck as in Fig. 1, said gasket is compressed between the flange portion 1 of the closure inner wall and the top 80 transverse wall 30 of the neck. Said gasket is of insufficient width to reach the cylindrical skirt portion 11 of the closure outer wall so that the vent opening or openings 22 in the margin of the horizontal flange portion 1 of the closure inner wall are not 85 covered thereby.

What I claim is:

1. A closure for the openings of devices having opposed cam portions adjacent said openings, comprising an element provided with two opposed openings, and a locking member having a body portion spaced from said element and provided with locking fingers extending through and movable in 95 said openings toward and from said element and with integral resilient means yieldingly engaging said element and normally tending to move said body portion and said fingers from said element, whereby when the closure is applied to a device for closing the opening thereof, the locking fingers of said closure engage the cam portions of said device with yielding effect.

2. A closure for the openings of devices having opposed cam portions adjacent said openings, comprising an element and a locking member having a body portion spaced from said element and provided with locking fingers having limited movement toward and from said element and with integral resilient means yieldingly engaging said element and normally tending to move said body portion and said fingers from said element, whereby when the closure is applied to a device for closing the opening 105 thereof, the locking fingers of said closure engage the cam portions of said device with 110 yielding effect.

3. A closure for the openings of devices having opposed cam portions adjacent said 115 openings, comprising an element and a locking member provided with locking fingers having limited movement toward and from said element and with a resilient arm yieldingly engaging said element and nor- 120

5 mally tending to move said fingers from said element, whereby when the closure is applied to a device for closing the opening thereof, the locking fingers of said closure engage the cam portions of said device with yielding effect.

10 4. A closure for the openings of devices having opposed cam portions adjacent said openings, comprising an element, and a locking member provided with locking fingers having limited movement toward and from said element and with resilient opposed arms yieldingly engaging said element and normally tending to move said fingers from said element, whereby when the closure is applied to a device for closing the opening thereof, the locking fingers of said closure engage the cam portions of said device with yielding effect.

15 5. A closure for the openings of devices having opposed cam portions adjacent said openings, comprising an element, and a locking member provided with locking fingers having limited movement toward and from said element and with a pair of resilient opposed arms extending in opposite directions into yielding engagement with said element and normally tending to move said fingers from said element, whereby when the closure is applied to a device for closing the opening thereof, the locking fingers of said closure engage the cam portions of said device with yielding effect.

20 6. A closure for the openings of devices having opposed cam portions adjacent said openings, comprising an element provided with two opposed openings, and a locking member provided with locking fingers extending through and movable in said openings toward and from said element and with a pair of resilient opposed arms extending in opposite directions into yielding engagement with said element and normally tending to move said fingers from said element, whereby when the closure is applied to a device for closing the opening thereof, the locking fingers of said closure engage the cam portions of said device with yielding effect.

25 7. A closure for the openings of devices having opposed cam portions adjacent said openings, comprising a member having a cup-shaped portion provided in its side wall with two opposed openings, and a locking member having a body portion arranged within said cup-shaped portion and finger portions at the ends of said body portion, said finger portions extending through and axially movable in said opposed openings, the body portion of said locking member being provided with a pair of resiliently opposed arms extending in opposite directions into yielding engagement with the bottom wall of said cup-shaped portion and normally tending to move said finger portions

from said bottom wall, whereby when the closure is applied to a device for closing the opening thereof, the locking fingers of said closure engage the cam portions of said device with yielding effect.

30 In testimony whereof I hereby affix my ⁷⁰ signature.
